US00D755855S

(12) **United States Design Patent**
Wooten(10) **Patent No.:** **US D755,855 S**
(45) **Date of Patent:** **** May 10, 2016**(54) **DISPLAY DEVICE WITH ICON**

- (71) Applicant: **BlackBerry Limited**, Waterloo (CA)
- (72) Inventor: **Steven Robert Wooten**, Mississauga (CA)
- (73) Assignee: **BlackBerry Limited**, Waterloo, Ontario (CA)
- (**) Term: **15 Years**
- (21) Appl. No.: **29/540,854**
- (22) Filed: **Sep. 29, 2015**
